UNITED STATES PATENT OFFICE.

HARRY L. HOENIGSBERGER, OF CHICAGO, ILLINOIS.

LAP-ROBE.

No. 823,469.

Specification of Letters Patent.

Patented June 12, 1906.

Application filed April 24, 1905. Serial No. 257,198.

To all whom it may concern:

Be it known that I, HARRY L. HOENIGSBERGER, a citizen of the United States, residing at Chicago, in the county of Cook and State of Illinois, have invented certain new and useful Improvements in Lap-Robes, of which the following is a specification.

This invention is intended more particularly for use by automobilists or drivers; and the objects of the invention are to provide a robe in the general form of a bag which can be quickly and easily adjusted to fit the body of the wearer and at the same time enable the wearer to remove the robe instantly and without difficulty in case of emergency.

Another object of the invention is to so construct the robe as to thoroughly protect the wearer against cold and to prevent displacement by wind or otherwise and allow the hands of the wearer to be unimpeded for the purpose of manipulating the automobile or other vehicle.

Another object of the invention is to so construct the robe that it will cling easily but firmly to the body of the wearer, whether sitting or standing, and provide a snug protection for the lower extremities of the body, obviating the necessity for tucking in the robe and constantly adjusting the same to keep it in place.

Another object of the invention is to provide a foot-pad adapted to keep the feet warm and at the same time allow perfect manipulation of the levers or clutches by the feet, which is essential to the operation of an automobile or similar vehicles, and at the same time the robe is so formed as to allow for the freedom of movement of the entire body without admitting the cold air at any point.

40 The nature of the robe permits its use by large or small persons of either sex, since the robe is adapted to adjust itself to the body without the necessity for providing buckles or other adjusting means.

45 The invention consists in the features of construction and combination of parts hereinafter described and claimed.

In the drawings, Figure 1 is a front view of the robe adjusted to the body of the wearer; 50 Fig. 2, a rear perspective view showing the robe opened for adjustment around the body; Fig. 3, a similar view showing the robe closed as in use; Fig. 4, a plan view of the spring for holding the robe in adjusted position; Fig. 5, 55 a rear elevation showing the robe closed; and

Fig. 6, a cross-section of the lower portion of the robe, showing the bifurcated formation.

The robe can be constructed of any suitable material—such as cloth, leather, fur, or felt—and is adapted to be lined or otherwise constructed in a manner to retain the heat of the body and prevent the admission of cold. 60

The robe as a whole is of bag formation; and it consists of a body portion *a*, closed at the front and split at the rear to leave edges *b* and *c*, adapted to be distended, as in Fig. 2, for the purpose of adjusting the robe to the body of the wearer. The bag is bifurcated at its lower end and closed by means of foot-pads *g* of suitable shape and size to provide for the necessary movement of the feet in operating an automobile or similar vehicle, and the bag is open at the top and provided with a seam or opening *e*, through which is inserted an oval spring *f*, split at the rear side to provide for distention. The spring is shaped to substantially conform to the curvature of the body and is normally contracted, as shown in Fig. 4, to hold the open end of the robe closely around the body of the wearer, and the free ends of the spring are adapted to overlap one another to a slight degree in order to form a close tight joint when the robe is adjusted. The spring is preferably made of resilient steel and its size and shape can be

resilient steel and its size and shape can be varied to suit the measurement of the intended wearer, although it is desirable to make the spring of sufficient resiliency to allow for the use of the same robe by persons of large or small size or of either sex. By overlapping the edges of the spring a considerable degree of expansion and contraction is provided for, and at the same time the spring is given sufficient tension to hold the robe snugly in place after adjustment, thereby obviating the necessity for frequently adjusting the robe and leaving the hands of the operator entirely free for the manipulation of the steering and controlling mechanism of the vehicle. This arrangement gives the feet a considerable degree of freedom and enables the manipulation of foot-levers or other appliances which are spaced a considerable distance from one another, as is often the case in the arrangement of the controlling mechanism on automobiles.

In use the robe is adjusted by opening the bag, as shown in Fig. 2, which allows the wearer to step thereinto, after which the robe is closed at the upper end by the tension of 110

the spring, which clasps the robe firmly and securely around the waist of the wearer and closes the seam at the back, allowing the operator to take his seat, and the robe requires no further adjustment. In case of emergency 5 the wearer can instantly remove the robe by spreading the open end, which allows him to discard the robe without difficulty, and ordinarily the robe can be removed by merely 10 grasping the front portion and drawing the robe from the body, which serves to expand the spring and allow the robe to be removed. The robe serves to protect the lower portion 15 of the body at all points and is much superior to an ordinary lap-robe in that all portions of the robe are utilized and the closure is complete, and at the same time the robe as a whole is less bulky and more comfortable than robes of the ordinary character. Furthermore, 20 there is no danger of the feet becoming entangled in the robe, and its removal can be more readily effected than that of an ordinary robe tucked in the usual way. The absence of buckles, snaps, or other adjusting 25 means enables the robe to be more quickly and easily positioned and at the same time permits the same robe to be used by persons of different measurement without readjustment. Moreover, where straps, clasps, or other ad-

justing means are employed difficulty will be 30 experienced in quickly removing the robe in case of emergency, which is a feature of great importance in the art to which the present invention relates.

What I regard as new, and desire to secure 35 by Letters Patent, is—

A lap-robe of bag formation open at the top and closed at the bottom for the reception of the feet and provided at the back with a split extending from the closed bottom to 40 the open top, the bottom being bifurcated to allow individual movement of the feet, the bag being of a size to allow the edges to the split to overlap each other very slightly to provide a close seam without interfering with the manipulation of the robe and a split hoop of 45 spring metal secured to the open top of the bag and adapted in combination with the closed bottom to normally hold the split closed from top to bottom when the bag is 50 being worn and adapting the bag to be removed from the body by distending the free ends of the spring.
